UNITED STATES PATENT OFFICE

EMIL F. HAGER, OF RICHMOND HILL, NEW YORK

DISPLAY DEVICE

Application filed February 28, 1928. Serial No. 257,613.

My invention relates to display devices of the conveying type and has for its main object to provide a device on which merchandise may be so uniquely displayed as to immediately arrest the attention of the casual observer and mystify and perplex him by its operation.

A further object is to provide a device of very attractive appearance, lending itself to a great variety of suggestive advertising displays, which may be substituted one for another without necessitating modifications or alterations of the mechanical features of the device; and on which may be displayed merchandise of all kinds, not only such as are contained in closed cans or packages, but also liquids and loose merchandise placed in open containers.

A still further object is to provide a display device which may be operated at a low cost, which have no parts easily broken or disarranged, which is easy to install, is automatic in its operation, and comparatively inexpensive to manufacture.

These and various other objects and advantages will be readily understood from the following description and from the accompanying drawings of a preferred embodiment, but it will be noted that certain modifications might be made without departing from the scope of the invention.

In the drawings:

Fig. 1 is a front elevation of the preferred embodiment of the invention,

Fig. 2 is a top view,

Fig. 3 is a front elevation with the front panel removed so as to show the interior,

Fig. 4 is a top view with the upper flooring removed.

Fig. 5 is a side elevation with the side panel removed.

Figs. 6 and 7 are fragmentary, side elevations of the lower part of the device showing certain details, and

Fig. 8 is a fragmentary, top view of Figs. 6 and 7. Certain parts have been omitted from several of the views so as to simplify the drawings.

In a general way the device may be said to consist of a cabinet the top of which, by

appropriate scenery, is converted into a stage across which merchandise is conveyed from one side to the other on platforms traveling on a continuous, oblong track. The platforms being loaded at one side and unloaded at the other side of the stage; the loading and unloading being hidden from view by the scenery. The platforms traveling in one direction carry merchandise while those going in the opposite direction are empty. The loading and unloading of the platforms is performed by two elevators and a conveyer operated and contained in the cabinet. A window is cut in the front panel of the cabinet, through which is exposed a moving, endless belt carrying an appropriate advertising legend.

Referring first to Figs. 1, 2 and 5, the device consists of a cabinet 10 and a stage 11. In the front panel 12 of the cabinet a window 13 is cut and through this is exposed the endless belt 14 with its printed advertisement. On the flooring 15 of the stage are erected a background 16, at the left side scenery 20, 21 and 22, and on the right side scenery 17, 18 and 19. The scenery forms a closed compartment at each end of the stage, hiding the interiors from the observer.

While no attempt has been made to show any scenic effect on the drawings, it will readily be understood that the parts 16, 17, 18, 19, 20, 21 and 22 may be decorated in any manner to suit the merchandise displayed, for example, the left-hand side of the stage might be made to represent a store, the background a street and the right-hand side a dwelling house.

An oblong, endless groove 23 is cut in the stage floor and by this is guided a plurality of platforms 24, each provided with a downwardly extending stud 25 which engages in the groove. The platforms are driven by pins 26 which engage in a chain 27 driven by the sprocket wheels 28 and 29. The chain and the gears are located under the floor and the turns at each end of the groove are concealed in the compartment on the stage. The means by which the sprocket wheel 28 is driven, will be explained later.

Referring now to Figs. 3 and 4, the floor

ing 30 of the cabinet 10 is connected to the stage flooring by means of four corner posts 31, 32, 33 and 34 and four intermediate posts 35. Four bearings 36, 37, 38 and 39 are secured on the cabinet floor and in these bearings the main shaft 40 and the driven shaft 41 are mounted. The device is operated from the main shaft 40, preferably by an electric motor connected direct to the shaft by a worm and worm-gear, but any other suitable means might be employed. Drums 42 and 43 are secured on the shafts 40 and 41, and on these a belt 44 is driven in the direction indicated by the arrow on Fig. 4.

At each end of the belt 44, elevators 45 and 46 are located, their recessed, top surfaces being aligned evenly with the top of the belt so that the merchandise may be transferred from and to the elevators by the belt in the manner to be explained later. The elevators are slidably mounted on the vertical supports 47 and 48 in which slots 49 and 50 are provided. Tongues 51 and 52, forming parts of the elevators, engage in these slots and are held in correct relation to the vertical supports by parts 53 and 54 which also act as counterweights in overcoming the tendency of the elevators to tilt when a load is placed upon them.

The elevators are raised and lowered in the following manner. Two long levers 55 and 56, pivoted in bearings 57 and 58, have their free ends engaged in slots 59 and 60 formed in brackets on the elevators, and each is provided with a roller 61 and 62. These rollers engage on a cam 63 which is secured on a shaft 64, mounted in bearings 65 and 66. This shaft is driven from the main shaft 40 by a chain 67 operated on sprocket wheels 68 and 69. It is evident that as the cam 63 rotates, the elevators will be lifted and lowered due to the shape of the cam-face.

As the merchandise, in this particular case cans 70 are illustrated, travels on the belt 44 in the direction indicated, they are, one at a time, pushed on the elevator 45 by the action of the belt. After the elevator 45 ascends the can is moved off the elevator and on to one of the platforms 24 by the rocker-lever 71. The actuating mechanism for this lever will be described later. When the platform reaches the other side of the stage the can is guided onto the elevator 46 by the guide 72. The elevators now descend and the can is returned to the belt 44 by means of the rocker-lever 73.

The rocker-levers 71 and 73 are actuated by the mechanism now to be described. Along bar 74 is reciprocatingly mounted in slots in the intermediate, front posts 35 and the bar is reciprocated by a cam lever 75 engaged between two rollers 76 and 77 which are mounted on the bar. Motion is imparted to the cam lever by a cam 78, mounted on the shaft 64 and engaging on its face with a roller 79

mounted on the cam lever. The contour of the cam face is such as to cause the bar to reciprocate and a tension spring 80 always keeps the roller 79 against the cam. The lever 71 is mounted on a shaft 81 rotating in a downwardly extending bearing 82 which is secured under the stage flooring, and to the lower end of this shaft a lever 83 is secured. The free end of this lever is provided with a slot 84 in which a pin 85, secured on the bar 74, engages. The lever 73 is rigidly mounted on a vertical shaft 86 on which is also rigidly mounted a lever 87. This lever is provided with a slot 88 at its outer end in which a pin, also mounted on the bar 74, engages. It will be plainly seen, that as the cam 78 rotates the levers 71 and 73 are rocked.

Referring now to Figs. 6, 7 and 8. The sprocket wheel 28 is driven by a chain 91 which passes over a sprocket wheel 90 mounted on the shaft 64 as well as over the idlers 92 and 93. These idlers are mounted on shafts in the bearings 94 and 95 which are suspended below the stage flooring on a block 96.

The belt 14 travels on pulleys 97, 98, 99 and 100 mounted on the vertical shafts which are formed integral with the corner posts 31, 32, 33 and 34. The belt is driven by a ball chain 101 which engages in a groove 102 formed near the top of the pulley 98. This ball chain is driven by a gear 103 mounted on the main shaft and passes over two idlers 104 and 105 which are angularly mounted under the stage flooring on the bearing 106. This bearing has been omitted in Fig. 8 but is plainly shown in Fig. 6.

As merchandise might accidentally be displaced while the device is in operation, an automatic, safety stop has been provided; this stop is only used when an electric motor is employed for driving the device. The stop consists of a sprocket wheel 107 rotatably mounted on shaft 64 and driven by a chain 108 actuated by a sprocket wheel 109 which is mounted on the main shaft 40. The sprocket wheel 107 is provided with a clutch 110 which engages on a clutch pin 111 secured in the shaft 64. A compression spring 112, adjusted by a cap screw 113 threaded into the end of the shaft, normally holds the clutch in engagement with the pin, but under increased friction the spring allows the clutch to disengage from the pin. An electric switch 114, having a lever arm 115, is so located that when the clutch is disengaged the lever arm operates the switch and breaks the electric current. To again start the device, the push button 116 is depressed. The switch is connected in series with the motor when such is employed and the chain 67, previously described, is removed.

As previously explained, the merchandise is conveyed along belt 44, up to the stage floor by elevator 45, over the stage by the platforms 130

24 and down again to the belt by elevator 46. Double doors 117 and 118 are formed in the partition 22 and these doors are opened by the platforms as they pass through. They are closed after the passage of each platform by the spring 119 which acts on the doors through the links 120, 121 and 122. Double doors 123 and 124 are also formed in partition 19 but these doors are opened by means 5 of a cam 125 which rocks a lever 126 secured on a vertical shaft 127 to which is also secured the door-opening mechanism. This consists of a lever 128 and three links 129, 130 and 131. The shaft is supported in bearings 132 and 133 and a tension spring 134 always tends 10 to hold the lever 126 in contact with the cam 125. The cam 125 is mounted on the shaft on which the sprocket wheel 29 is also mounted.

20 It will be seen that all that is disclosed to the observer are the objects carried across the stage and the empty platforms moving in the opposite direction, the rest of the conveying mechanism being hidden. To make the operation 25 of the device still more perplexing, the platforms are painted in various colors or otherwise differentiated. In this manner, if different objects are carried on the conveyer they will be carried on a different platform 30 each time they pass across the stage; this is due to the difference in carrying capacity of the two conveyers.

It will be understood that I do not wish to limit the invention to just the embodiment 35 illustrated, but that I expect to utilize it to the full extent of the annexed claims.

Having described my invention, what I claim as new and wish to protect by Letters Patent is:

40 1. In a conveyer of the class described, a lower conveyer, an upper conveyer, elevators connecting with both ends of said conveyers, said elevators operated by a pair of crossed levers actuated by a rotating cam, and means for transferring objects from said conveyers to said elevators and from said elevators to said conveyers.

2. In a conveyer of the class described; a lower, belt conveyer; an upper, horizontal, 50 chain conveyer; elevators connecting with both ends of said conveyers; said elevators operated by a pair of crossed levers actuated by a rotating cam; and means for transferring objects from said conveyers to said elevators and from said elevators to said conveyers.

3. In a conveyer of the class described; a lower, belt conveyer; an upper, horizontal, 60 chain conveyer provided with individual object-carrying platforms; elevators connecting with both ends of said conveyers; said elevators operated by a pair of crossed levers actuated by a rotating cam; and means for transferring objects from said conveyers to said elevators to said belt conveyer and said platforms and from said belt conveyer and plat-

said elevators and from said elevators to said conveyers.

4. In a device of the class described, a belt conveyer concealed in a cabinet, a horizontal chain conveyer provided with object-carrying platforms and operated in the top of said cabinet, elevators connecting with both ends of said conveyers, said elevators operated by a pair of crossed levers actuated by a rotating cam, and means for transferring objects from said conveyers to said elevator and from said elevators to said conveyers. 70

5. In a device of the class described; a belt conveyer concealed in a cabinet, a horizontal chain conveyer having object-carrying platforms operated on top of said cabinet, elevators connected with both ends of both of said conveyers, said elevators operated by a pair of crossed levers actuated by a rotating cam, means for transferring objects from said elevators to said belt conveyer and said platforms and from said belt conveyer and platforms to said elevators, and suitable scenery erected on top of said cabinet. 80

6. In a device of the class described, a belt conveyer concealed in a cabinet, a horizontal chain conveyer having object-carrying platforms operated on top of said cabinet, elevators connected with both ends of both of said conveyers, said elevators operated by a pair of crossed levers actuated by a rotating cam, means for transferring objects from said elevators to said belt conveyer and said platforms and from said belt conveyer and platforms to said elevators, suitable scenery erected on top of said cabinet, and said scenery so constructed as to conceal both ends of said chain conveyer but allow the passage of said platforms and the objects carried thereon. 90

7. In a device of the class described, a belt conveyer concealed in a cabinet, a horizontal chain conveyer, having object-carrying platforms operated on top of said cabinet, elevators connected with both ends of both of said conveyers, said elevators operated by a pair of crossed levers actuated by a rotating cam, means for transferring objects from said elevators to said belt conveyer and said platforms and from said belt conveyer and platforms to said elevators, suitable scenery erected on top of said cabinet, said scenery so constructed as to conceal both ends of said chain conveyer, and automatically operated doors provided in said scenery. 100

8. In a device of the class described, a belt conveyer concealed in a cabinet, a horizontal chain conveyer having object-carrying platforms operated on top of said cabinet, elevators connected with both ends of both of said conveyers, said elevators operated by a pair of crossed levers actuated by a rotating cam, means for transferring objects from said elevator to said belt conveyer and said platforms and from said belt conveyer and plat-

forms to said elevators, suitable scenery erected on top of said cabinet, said scenery so constructed as to conceal both ends of said chain conveyer, automatically operated doors provided in said scenery, and the object-carrying platforms so marked as to be distinguishable one from another.

9. In a device of the class described, a belt conveyer concealed in a cabinet, a horizontal chain conveyer having object-carrying platforms operated on top of said cabinet, elevators connected with both ends of both of said conveyers, said elevators operated by a pair of crossed levers actuated by a rotating cam, means for transferring objects from said elevators to said belt conveyer and said platform and from said belt conveyer and platforms to said elevators, and automatic means for stopping the device should any object conveyed thereon become displaced.

EMIL F. HAGER.
